PROCESS OF FORMING NAPHTHENIC ACID SOLUTIONS

Rudolf Kern, Neustadt, Hans Scheurer, Heidelberg, Hermann Zorn, Mannheim, and Eugen Kruppke, Heidelberg, Germany, assignors to Firma Rhein-Chemie G.m.b.H., Heidelberg, Germany

No Drawing. Application April 3, 1953
Serial No. 346,784

Claims priority, application Germany April 12, 1952

27 Claims. (Cl. 252—37)

The present invention relates to naphthenic acid solutions and processes of making the same and more particularly to liquid hydrocarbon solutions of naphthenic acid salts which are especially suitable for motor oils and lubricating oils.

Naphthenic acid salts have been utilized in mixture with organic solvents and particularly hydrocarbons in various chemical fields, especially for the manufacture of impregnating agents, pesticides, plastics, etc.

Naphthenic acid salts have also been added to motor oils and lubricating oils in order that the cation of the naphthenic acid salt might react with and neutralize the free sulfuric acid which is formed upon burning of the sulfur-containing oil. Mainly polyvalent metal salts of naphthenic acid were utilized for this purpose, i.e. barium and aluminum naphthenates. However, the use of these naphthenic acid salts was greatly limited and made extremely difficult because of the physical characteristics of the same, particularly when mixed with liquid hydrocarbons.

The naphthenic acid salts are either insoluble or only difficultly soluble in hydrocarbons, or the naphthenates form gels with the hydrocarbons. The naphthenic acid salts therefore greatly increase the viscosity of the hydrocarbons to which they are added. This increase in viscosity is highly detrimental for many purposes and therefore prevents the use of the naphthenic acid salts and particularly the polyvalent metal salts of naphthenic acid for such purposes.

It has been attempted to overcome these drawbacks in the use of naphthenic acid salts by the addition thereto of many different substances. However until the present time none of these additions have proved successful and the difficult solubility of the naphthenic acid salts and the high viscosities of the solutions of the naphthenic acid salts in hydrocarbons has proved to be an important problem in many industries.

It is therefore an object of the present invention to provide means for dissolving naphthenic acid salts in liquid hydrocarbons and hydrocarbon oils consisting of mixtures of hydrocarbons whereby greater quantities of the naphthenic acid salts can be dissolved in the liquid hydrocarbon without unduly increasing the viscosity of the hydrocarbon.

It is a further object of the present invention to provide for means of dissolving naphthenic acid salts in liquid hydrocarbons whereby the viscosity of the naphthenate-containing liquid hydrocarbon is much lower than the viscosity of the ordinary hydrocarbon solutions of naphthenic acid salts containing the same amount of naphthenate and whereby the resinification products and other decomposition products of the liquid hydrocarbon oils are dissolved or dispersed in the hydrocarbon.

It is a still further object of the present invention to provide for the formation of clear solutions of naphthenic acid salts in liquid hydrocarbons.

It is another object of the present invention to pro-

2

vide a group of compounds any member or members of which may be utilized as intermediates for the dissolution of naphthenic acid salts in liquid hydrocarbons.

It is still another object of the present invention to provide a second group of compounds which when utilized in addition to the first group of compounds further increases the dissolving ability of liquid hydrocarbons for naphthenic acid salts, the second group of compounds increasing the effect of the first group of compounds when utilized simultaneously therewith.

With the above objects in view, the present invention mainly comprises in a process of forming hydrocarbon and hydrocarbon oil solutions of naphthenic acid salts, the step of mixing a naphthenic acid salt with a liquid hydrocarbon and with at least one substance having the general formula: $XO-(R-O)_n-R-OY$, wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of the groups X and Y is selected from the class consisting of alkyl, aryl, aralkyl, alkaryl, alicyclic and acyl radicals having at least 6 carbon atoms.

The above group of compounds represented by the general formula $XO-(R-O)_n-R-OY$ will hereinafter be referred for convenience as solvent A.

It has been found according to the present invention that solvent A increases the solubility of the naphthenic acid salts in the liquid hydrocarbons either by serving as intermediate solvent therefor or by some unknown action. The manner in which the solvent A works is unimportant, the present invention not being limited to any theory of operation but rather to the fact that solvent A does have the desired action.

In addition it has been found that the incorporation of a second group of substances having the general formula: $R'-O-R''$ wherein R' and R'' are alkyl, aryl, aralkyl, alkaryl or alicyclic groups and at least one of the groups R' and R'' contains at least 6 carbon atoms further increases the dissolving ability of the liquid hydrocarbon for the naphthenic acid salts. This second group of substances will hereinafter be referred to as solvent B.

It should be noted that solvent B may be utilized in addition to solvent A and not in place of solvent A. Solvent A is absolutely necessary for the sufficient improvement in the dissolution of the naphthenic acid salts in the liquid hydrocarbons. Solvent B when used in addition to solvent A provides the advantage of forming clear solutions of the naphthenic acid salts.

The term "naphthenic acid salts" refers to any metal salt of naphthenic acid and particularly polyvalent metal salts of naphthenic acid. Aluminum naphthenate, barium naphthenate, calcium naphthenate, zinc naphthenate, iron naphthenate, lead naphthenate, potassium naphthenate, and the like naphthenates are examples of naphthenic acid salts which may have the solubility thereof in hydrocarbons increased according to the present invention, the scope of said invention now however being limited to the specific naphthenates mentioned.

As stated above, solvent A has the general formula: $XO-(R-O)_n-R-OY$ wherein R is an alkylene radical of 2 or 3 carbon atoms, n is a whole number between 1 and 20 and either X or Y is a hydrogen, alkyl, aryl, aralkyl, alkaryl, alicyclic or acyl radical of any number of carbon atoms and the other of the groups X and Y is an alkyl, aryl, aralkyl, alkaryl, alicyclic or acyl radical of at least 6 carbon atoms.

It is preferred that n be between 2 and 7. It is further preferred that the radical X or Y which must be of at least 6 carbon atoms, be of at least 8 carbon atoms,

and still more preferably that it be exactly 12 carbon atoms. There is no actual maximum as to the number of carbon atoms for the groups X and Y, though as a practical matter X and/or Y should not have more than 24 carbon atoms.

In the above given general formula for solvent A, it may be seen that the portion: O—(R—O)_n—R—O of the compound is symmetrical and therefore any radical which may be substituted for X may equally be substituted for Y. Thus, either or both X and/or Y may be substituted by an alkyl, aryl, aralkyl, alkaryl, alicyclic or an acyl group. Either X or Y, but not both, may be substituted by a hydrogen radical. If one of the groups X or Y is substituted by a hydrogen radical, then the other group must be substituted by an alkyl, aryl, aralkyl, alkaryl, alicyclic or an acyl radical of at least 6, preferably at least 8 and most preferably exactly 12 carbon atoms. If both groups X and Y are substituted by alkyl, aryl, aralkyl, alkaryl, alicyclic or acyl radicals, then only one of the groups must be of at least 6 carbon atoms, although both groups may be of at least 6 carbon atoms. The alkyl, aryl, aralkyl, alkaryl, alicyclic or acyl groups may be either saturated or unsaturated.

It is therefore apparent that solvent A is either an esterified or etherified polyalkylene glycol or esterified or etherified ester or ether derivative of polyalkylene glycol in which there are at least 2 and at most 21 alkylene groups and in which the polyalkylene glycol is esterified or etherified with at least one radical having at least 6 carbon atoms. The solvent A may be a monoether, a diether, a monoester, a diester, or an ether-ester of polyalkylene glycol. Preferably the solvent A will contain five alkylene groups and the alkyl, aryl, aralkyl, alkaryl, alicyclic or acyl group will contain 12 carbon atoms.

The following are examples of different compounds which may be utilized as solvent A according to the present invention. It is to be understood that these examples are given for illustrative purposes only and the scope of the present invention is in no way meant to be limited to the specific compounds mentioned.

The following are examples of monoethers of polyalkylene glycol:

Dodecylpentaethylene glycol, octadecenyl-hexaethylene glycol, laurylpentaethylene glycol, 2-ethylhexylpentaethylene glycol, nonylheptaethylene glycol, phenylethylpentaethylene glycol, methyl-cyclohexylctaethylene glycol, p-octylphenyltetrapropylene glycol, dodecylcyclohexyl-hexapropylene glycol, hexylnaphthyltetraethylene glycol and hexylnaphthyltetrapropylene glycol.

The following are examples of diethers of polyalkylene glycol:

Dodecyl- or laurylpentaethyleneglycolmethyl ether (the term lauryl should be understood as designating the radical from fatty alcohol produced from coconut fatty acids), p-octylphenyl-tetraethyleneglycolisopropylether, octydecenyl-hexaethyleneglycol-ethylhexyl ether, 2-ethylhexyl-heptaethylene glycolbenzylether, etc. It is to be noted that any alcohol may be utilized for the esterification of the polyalkylene glycol, including alcohols obtained by the reduction of natural or synthetic fatty acids, by the carbon monoxide hydrogenation at normal or raised pressure, by the oxo-synthesis or by paraffin oxidation.

The following are examples of mono and diesters of polyalkylene glycol and of ethers of polyalkylene glycol:

Pentaethyleneglycol-monostearate, hexaethylene-glycol-monostearate, dodecylbenzyl-pentapropylene glycol-oleate stearoyl-pentaethylene glycol-isopropylether stearoyl-pentapropylene glycol-isopropylether, benzoylpentaethylene-glycol-oleate, benzoylheptaethylene- or propylene-octylether, and benzoylpentaethyleneglycolmethyl ether.

The production of solutions of naphthenic acid salts in hydrocarbons according to the process of the present invention can be accomplished in various ways. The

method of proceeding depends upon the specific naphthenate, polyalkylene glycol derivative and the hydrocarbon oil in which the substances are mixed. It is preferable, although not necessary, to work at raised temperatures i.e. between 90-150° C.

The components, namely the naphthenate, polyalkylene glycol derivative and the hydrocarbon oil may be mixed together, preferably while stirring and at raised temperature, or the polyalkylene glycol derivative may be first mixed with the hydrocarbon and then the naphthenic acid salt added, or the naphthenic acid salt may be mixed with the hydrocarbon and the polyalkylene glycol derivative added, or the polyalkylene glycol derivative first mixed with the naphthenic acid salt and the thus formed solution then added to the liquid hydrocarbon.

The amount of solvent A, namely the polyalkylene glycol derivative, can be varied within very wide ranges, for example from 1% by weight of the amount of naphthenate to equal or even more than the amount of naphthenate. The specific amount depends upon the type of naphthenate as well as upon the use to which the hydrocarbon solution of the naphthenate is to be put and on the desired viscosity of the final solution. Anyone skilled in the art can by simple pretesting determine the exact amount of solvent A to be utilized for any given purpose.

The following examples are given as illustrative of the process of the present invention specifically with the use of different compounds as solvent A. It is to be understood that these examples are in no way meant to limit the scope of the present invention.

Example I

To a gel consisting of 20 parts aluminum naphthenate and 80 parts of purified light petroleum is added while stirring at a temperature of 25° C., 5 parts of pentapropylene-glycoldodecylether. This causes a sudden change from gelatinous condition to a thinly liquid, easily pourable solution.

Example II

The great viscosity-lowering effect of laurylpentapropylene glycol is illustrated by mixing with mineral oils containing various naphthenic acid salts. This is shown on the following table. The various naphthenic acid salts in the amounts given in the table were each stirred with 100 parts by weight of a mineral oil (specific gravity at 20° C.—0.882; viscosity index—89; coking number according to Conradson—0.11; and portion insoluble in gasoline—0) at a temperature of 100-110° C. until a homogeneous mixture was obtained and the viscosities of these mixtures were measured at 80° C. or 50° C. as indicated. The same solutions were then mixed with the given parts by weight of laurylpentapropylene-glycolether and the viscosity of these solutions were measured at 80° C. or 50° C., as indicated.

Naphthenate	Parts by Weight	Parts by Weight laurylpentapropylene glycol ether	Viscosity	
			temp. in ° C.	cst.
Aluminum naphthenate.....	1	0.4	80	27.59
Do.....	1	0.4	80	19.80
Aluminum and Calcium naphthenate.....	5+5	4	80	49.99
Do.....	5+5	4	80	30.00
Zinc naphthenate.....	30	4	80	72.76
Do.....	30	4	80	37.04
Iron naphthenate.....	30	4	50	119.02
Do.....	30	4	50	108.20
Lead naphthenate.....	30	4	50	85.20
Do.....	30	4	50	78

Example III

The viscosity lowering effect of polyalkylene glycol derivatives is also achieved on naphthenate solutions which already have a low viscosity. A solution of 30

parts by weight calcium naphthenate in 100 parts by weight of a hydrocarbon of diesel oil character has at 80° C. a viscosity of 3.02 cst. The addition of 8 parts by weight of methylheptaethyleneglycolnaphthenicacid-ester to 100 parts by weight of the solution causes a 5 lowering of the viscosity at 80° C. to 2.74 cst.

Example IV

Mineral oil having the viscosity at 80° C. of 18.70 cst. has the viscosity thereof increased by dissolving 10% 10 by weight of potassium naphthenate therein, to a value at 80° C. of 29.5 cst. An addition of 20% decylpentapropyleneglycoether causes a reduction of the viscosity at 80° C. to 21.26 cst. A methyl ether or the benzoate of the polyalkyleneglycoether mentioned above will 15 have the same effect.

Example V

100 parts by weight of Tetralin and 20 parts by weight of barium naphthenate result in a solution having an 20 average viscosity at 80° C. of 15.5 cst. The addition to 100 parts by weight of this solution of 10 parts by weight of laurylpentaethyleneglycoether results in a lowering of the viscosity at 80° C. to 1.76 cst.

Example VI

Neutral barium naphthenate from distilled naphthenic acid having an acid number of 180 and is in the form of a brittle resin at room temperature, in gummy state at a temperature of 100° C. and has a drop-forming temperature of more than 230° C. This substance is extremely difficult to dissolve in mineral oil and after cooling a solution of the same in mineral oil a heavy gelatin-like mass is formed.

A fatty alcohol having a hydroxyl number of 6.8 obtained by high pressure hydrogenation of paraffin-oxidized fatty acid forms with 5 moles of ethylene oxide using an alkali as catalyst of the oxethylation a waxy mass at room temperature having a drop-forming point of 38° C.

By mixing 40 parts of the brittle barium naphthenate with 15 parts of the polyglycol ether at 100° C. while stirring, the gummy-like structure of the substance is changed and upon cooling a thread-drawing syrup is obtained which is easily soluble in hydrocarbons without the formation of any undissolved residues.

In addition to the above described polyalkylene glycol derivatives which serve as solvent A, it is desirable to add a high boiling point ether (solvent B) to the mixture to increase the dissolving ability of the hydrocarbon and to further lower the viscosity of the formed solution. The high boiling point ethers which serve as solvent B are monoethers having the general formula R'-O-R" wherein at least one of the radicals R' and R" consists of 6 or more carbon atoms. The radicals R' and R" may be aliphatic, aromatic, or alicyclic and may be derived from mono- or polyhydric alcohols. However, in the event that the radical is derived from a polyhydric alcohol, the polyhydric alcohol must not have any ether linkages in the molecule except the single ether linkage with the other radical, namely R' or R". In other words the high boiling point ether must have only one ether linkage so that the same is free of polyalkylene glycol groups. It is this lack of polyalkylene glycol groups of solvent B which is the distinguishing feature between solvent B and solvent A. It is advantageous that the high boiling point monoether serving as solvent B be liquid at room temperature.

It has been found according to the present invention that the high boiling point ethers of solvent B seem to 70 serve as intermediate solvent not only for the naphthenic acid salts but also for the solvent A in the hydrocarbon solvent.

The following are examples of high boiling point mono-ethers according to the present invention. It is 75

to be understood that these are illustrative only of the many compounds which may be used as solvent B and the scope of the present invention is in no way limited to the specific compounds mentioned:

Di-n-hexylether, di-n-octylether, di-n-nonyl-ether, di-2-ethylhexylether, lauryl-2-ethylhexylether, octadecen-9-yl-1-isobutylether, dodecylphenylether, laurylcyclohexylether, octyl-B-tetraloether, nonyl-4-methyl-cyclohexylether, 4- octylphenyl- 2-ethylhexylether, etc. Benzyl ethers or alkyl substituted benzyl ethers of the above named or other aliphatic or alicyclic alcohols may also be used, i.e. nonylbenzylether, octadecenyl-4-methylbenzylether, di-benzylether, tetrahydronaphthylmethyl-phenyl- or benzylether, tetrahydronaphthylmethyl-2-ethylhexylether, butandiol-(1,3)-monoocystylether, butandiol-(1,4)-dibenzylether, and butandiol-(1,4)-isobutyl-dodecylether.

As may be seen from the above, at least one of the radicals R' and R" must be of at least 6 carbon atoms. There is no actual limit to the number of carbon atoms of either or both of the radicals though as a practical matter, radicals having less than 24 carbon atoms are preferred.

25 Ethers from paraffin fatty alcohols or their first runnings upon distillation as well as the oxo- or naphthene alcohols are particularly suitable, i.e. paraffin fatty alkyl-cyclohexylether, the first running upon distillation of dodecylalkylether, etc. The term "first running" is to be understood as meaning the first distillate of a mixture of alcohols obtained from high pressure hydrogenation of paraffin fatty acids whereby the alcohols of the mixture have a chain length of 6-9 carbon atoms.

30 The naphthenic acids are those obtained by raffination of mineral oils, which by high pressure reduction or by the process of Bouveault-Blanc may be transformed into the corresponding naphthene alcohol which may be easily reacted to form the ether. As examples of ethers which may be produced by the above described methods are, dinaphthenylether, and naphthenyl-benzyl- and -2- ethylhexylether.

35 It is possible to use either single ether or mixtures of two or more ethers or ether solutions or mixtures of ethers in hydrocarbons and hydrocarbon oils.

40 The application of a high boiling point monoether, namely solvent B increases the dissolvability of the naphthenic acid salts in the hydrocarbon or hydrocarbon oil. Whereas a mixture of a naphthenate with a solvent A at room temperature may form a waxy mass, the addition of 45 20% of a solvent B or mixture of ethers constituting the solvent B, transforms the waxy mass into a clear solution. The resulting clear solution may be easily diluted with a liquid hydrocarbon.

45 Besides acting as intermediate solvent, the ethers of solvent B also have the effect of lowering the viscosity of 50 solutions of naphthenic acid salts, solvent A and hydrocarbon.

55 The amount of high boiling point monoether which may be utilized varies within very wide limits i.e. from 60 very small amounts to twice the amount of a naphthenate and solvent A, or even more. The amount of solvent B is not only dependent upon the type and amount of naphthenic acid salt or mixture of naphthenic acid salt with solvent A, but also upon the degree of solubility which is desired and the desired miscibility of the naphthenic acid salt in the liquid hydrocarbon and also upon the desired viscosity of the final solution.

65 The production of naphthenic acid salt solutions in liquid hydrocarbons in the presence of at least one solvent A and at least one solvent B may be accomplished in many ways. For example the naphthenate may first be dissolved in the solvent B and the solvent A solution added thereto; and then adding the hydrocarbon oil thereto. It is also possible to first form a solution or paste of the naphthenic acid salt and the solvent A and

to then add to this mixture a solvent B; and finally to add a liquid hydrocarbon to the combined mixture. It is also possible to first form a solution of the liquid hydrocarbon, solvent A and solvent B and to dissolve the naphthenic acid salt in the thus formed solution. It is still further possible to dissolve the naphthenic acid salt in solvent B and to dissolve solvent A in solvent B and then mix the two solutions to form a single solution thereof which may be easily mixed with a liquid hydrocarbon.

The following examples are given as illustrative of the use of a solvent B in addition to a solvent A for the production of solutions of naphthenic acid salt.

Example VII

This example illustrates how the addition of a solvent B forms a clear solution of a naphthenate in a solvent A. Various naphthenates of the cations indicated in the following table were mixed with the polyalkylene glycol derivative indicated in the table in the proportion of 10:1 at a temperature of 40-80° C. Upon cooling a waxy mass was obtained. This mixture was then mixed in proportion of 1:1 with a solvent B ether indicated in the table. The addition of the ether to the mixture resulted in every case in the formation of a thin liquid solution which could be easily dissolved in a hydrocarbon.

Cation	Polyalkyleneglycol-derivative	Ether
potassium	naphthenic acid-hepta-alkyleneglycolester.	ethylhexyl-benzyl ether.
tin**	dodecyl-pentaethylene-glycolmethylether.	lauryl-n-butylether.
lead	benzylpentapropylene-glycolbenzoate.	diocetyl-ether.
iron***	p-octylphenyltetrapropylene-glycolether.	dibenzylether.
aluminum/calcium	stearyl-hexaethylene-glycolbenzoate.	tetradecylmethyl cyclohexylether.

Example VIII

Neutral aluminum naphthenate is very poorly soluble in a hydrocarbon such as petroleum or mineral oil. By stirring for a long time at a raised temperature of 100° C. a solution is formed which is in the form of a tough gel which upon cooling becomes non-homogeneous, a portion of the petroleum or mineral oil separating therefrom. The viscosity which is very difficult to measure with the above solution may be judged to be approximately 6000 cst. at 80° C. This gel is unsuitable for all technical purposes wherein a solution of aluminum naphthenate is desired. An addition of 4% laurylpentapropylene-glycolether lowers the viscosity of the aluminum naphthenate solution in the hydrocarbon from a value above 6000 to about 160 cst.

It is further preferable to first dissolve the aluminum naphthenate in a high boiling ether of solvent B. By dissolving 10 parts by weight aluminum naphthenate in 100 parts dodecyl-2-ethylhexylether a solution having a viscosity of 1890 cst. at 80° C. is obtained. The viscosity is further lowered by the addition of 4% laurylpentapropylene glycol to about 99 cst. This solution is miscible in all proportions with hydrocarbons and results in the formation of thin fluid solutions.

Example IX

A solution of 50% calcium naphthenate in dodecyl-octylether has a viscosity of 18.60 cst. at a temperature of 80° C. and upon the addition of 10% dodecylpentapentaethylene-glycolether the viscosity is lowered to 11.4 cst.

Example X

The lowering of the viscosity of the mixture of 60 parts barium naphthenate and 30 parts laurylpenta-

8
ethyleneglycoether by the addition of varying amounts of laurylethylhexylether is shown in the following table:

Percent by weight of laurylethylhexylether added	Viscosity of the mixture at 80° C. in cst.
0	122.0
20	38.1
40	18.5
60	12.5
80	9.2
100	7.7

Example XI

15 A 50% solution of barium naphthenate in a hydrocarbon such as of the spindle oil type can be formed only with very great difficulties and is unsuitable for all technical purposes. A solution of equal concentration of the 20 naphthenate in laurylethylhexylether is comparatively easy to produce and has a viscosity of 2335 cst. at 80° C. By the addition to the above of a polyalkylene-glycol derivative the viscosity is lowered. The lowering of the viscosity is dependent to some extent on the degree of 25 polymerization of the polyalkylene-glycol derivative. This is illustrated as follows:

	Viscosity at 80° C., cst.
20% lauryl-triethyleneglycoether	11.80
20% lauryl-pentaethylene-glycoether	11.94
30 20% lauryl-heptaethylene-glycoether	13.38

If the viscosity lowering substance laurylhexaethyleneglycoether is further etherified with ethylhexanol to laurylhexaglycoethylhexylether, the viscosity lowering remains within the same limits and the 20% addition will result in a solution having a viscosity of 13.64 cst.

Any of the above solutions may be easily mixed with liquid hydrocarbons.

Example XII

40 This example illustrates the viscosity lowering effect of 45 various polyalkylene-glycol derivative on a 50% barium naphthenate solution in laurylethylhexylether. The original solution has the viscosity of 3255 at 80° C. The polyalkylene-glycol derivatives indicated were added in an amount of 20% and the resulting viscosity at 80° C. was as indicated:

	Cst.
Benzylpentapropylene-glycoether	10.4
Octylphenoloctapropylene-glycoether	15.5
Stearicacid heptapropylene-glycoether	14.0

55 The addition of the naphthenic acid salts to a motor oil by means of a solvent A with or without a solvent B improves the activity of the motor oil even at low temperatures of i.e. 40-50° C. Likewise the addition to a lubricating oil also increases the action of the lubricating oil. The amount to be added to the motor oil or lubricating oil depends upon the sulfur content of the oil, and other properties and characteristics thereof. The amount may vary within rather wide limits, though generally amounts between 0.5-10% by weight of the naphthenate and solvent A with or without solvent B is suitable.

60 The following examples are given to illustrate the use of the present invention on the formation of motor and lubricating oils of improved properties.

Example XIII

A mixture is formed of:

70 40 parts laurylethylhexylether
15 parts of a pentaethylene-glycoether of a fatty alcohol obtained by high pressure hydrogenation of a paraffin-oxygenated fatty acid having a hydroxyl number of 6.6
40 parts barium naphthenate and
75 5 parts p-ethylhexylphenol

5 parts of this mixture is mixed with 95 parts of a basic paraffin oil having the following properties:

Specific gravity at 30° C. 0.885
Flash point ° C. 225
Viscosity at 50° C. cst. 65.8

In a diesel motor measuring device the above motor oil mixture is found to have the following characteristics:

Oil temperature 100° C.; and testing time 120 hours with a full load. The oil utilized was Middle East diesel oil having the sulfur content of 1%.

Upon ending the test run all the piston rings were freely movable and showed no slime or carbon deposits. The outside as well as the inside of the piston rings had a predominantly metallic appearance.

Tests as to the lubricating properties of the used oil on an Almen-Wieland machine gave a u-value between 0.2-0.1 with a possible load of 28 plates (1400 kg.).

Example XIV

The following mixture was tested:

65 parts lauryl ethylhexylether
15 parts laurylpentapropylene glycol ether
36 parts barium naphthenate
5 parts ethylhexylphenol

To a basic paraffin oil as in Example XIII was added 10% by weight of the above mixture and the resulting mixture was tested as a motor oil. The driving distance was 6000 kilometers without any oil change, the used oil only being replaced.

Upon ending the test drive the piston rings and the oil scraper rings were freely movable and no carbon or slime deposits were found in the piston grooves. The piston surface and cylinder walls had a true metallic appearance.

Tests as to the lubricating properties of the used oil in the Almen-Wieland machine showed a u-value between 0.1 and 0.2 and with a possible load of 20 plates (1000 kg.).

Example XV

In a two stroke diesel engine the following mixture as an addition of 10% to the above lubricating oil was tested:

20 parts barium naphthenate
15 parts calcium naphthenate
15 parts napthenealcohol-hexaethyleneglycolether
45 parts diethyl ether
5 parts di-tertiary-butyl-p-cresol

After a ten hour test run at 4500 revolutions per minute and at a water temperature of 95° C. the piston rings were freely movable and the surfaces thereof were of metallic appearance both on the inner and on the outer surface.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A process of forming liquid hydrocarbon solutions of naphthenic acid salts, comprising the steps of mixing a naphthenic acid salt with a liquid hydrocarbon at a temperature of 90-150° C.; and adding at said temperature to the thus formed mixture at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms in an amount sufficient to form a solution of said naphthenic acid salt, said liquid hydrocarbon and said substance.

2. A process of forming liquid hydrocarbon solutions of naphthenic acid salts, comprising the steps of mixing at a temperature of 90-150° C. a liquid hydrocarbon with at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms; and adding at said temperature to the thus formed mixture a naphthenic acid salt, said substance being present in an amount sufficient to form a solution of said liquid hydrocarbon, said naphthenic acid salt and said substance.

3. A process of forming liquid hydrocarbon solutions of naphthenic acid salts, comprising the steps of mixing at a temperature of 90-150° C. a naphthenic acid salt with at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms;

45 and adding at room temperature to the thus formed mixture a liquid hydrocarbon, said substance being present in an amount sufficient to form a solution of said liquid hydrocarbon, said naphthenic acid salt and said substance.

4. A process of forming liquid hydrocarbon solutions of naphthenic acid salts, comprising the steps of dissolving a naphthenic acid salt in at least one warm substance having the general formula:

55 wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic, and acyl radicals and the other of said groups X and Y is selected from the class consisting of alkyl, aryl, aralkyl, alkaryl, alicyclic and acyl radicals having at least 6 carbon atoms;

60 adding to the thus formed solution at least one high boiling point monoether having the general formula:

70 wherein R' and R'' are selected from the group consisting of alkyl, aryl, aralkyl, alkaryl, and alicyclic radicals and at least one of the groups R' and R'' contains at least 6 carbon atoms, thereby forming a combined solution thereof; and adding a liquid hydrocarbon to the thus formed combined solution said substance and said high boiling point monoether being present in an amount sufficient to form a solution of said liquid hydrocarbon,

said naphthenic acid salt, said substance and said high boiling point monoether.

5. A process of forming liquid hydrocarbon and hydrocarbon oil solutions of naphthenic acid salts, comprising the steps of dissolving a naphthenic acid salt in at least one high boiling point monoether having the general formula:

wherein R' and R'' are selected from the group consisting alkyl, aryl, aralkyl, alkaryl, and alicyclic radicals and at least one of the groups R' and R'' contains at least 6 carbon atoms; adding to the thus formed solution at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms, said substance being in an amount of 1% to equal the weight of said naphthenic acid salt, and said high boiling point monoether being in an amount up to two-times the amount of said naphthenic acid salt plus said substance, thereby forming a combined solution, of said naphthenic acid salt, said substance and said high boiling point monoether and mixing the thus-formed combined solution with a liquid hydrocarbon, thereby forming a hydrocarbon naphthenic acid salt solution the proportions of which may be varied in all proportions while still retaining a true solution.

6. As a new product, a hydrocarbon motor oil containing in solution between 0.5-10% by weight of a naphthenic acid salt and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms, said substance being present in an amount from 1% to equal the weight of said naphthenic acid salt.

7. As a new product, a hydrocarbon lubricating oil containing in solution between 0.5-10% by weight of a naphthenic acid salt and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms, said substance being present in an amount from 1% to equal the weight of said naphthenic acid salt.

8. As a new product, a hydrocarbon motor oil containing in solution between 0.5-10% by weight of a naphthenic acid salt, at least one substance having the general formula:

wherein R is an alkylene radical having a minimum of 2 and a maximum of 3 carbon atoms, n is a whole number

between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms, said substance being present in an amount from 1% to equal the weight of said naphthenic acid salt and at least one high boiling point monoether having the general formula:

wherein R' and R'' are selected from the group consisting of alkyl, aryl, aralkyl, alkaryl, and alicyclic radicals and at least one of the groups R' and R'' contains at least 6 carbon atoms, said high boiling point monoether being present in an amount of 10% to up to two times the weight of said naphthenic acid salt plus said substance.

9. As a new product, a hydrocarbon lubricating oil containing in solution between 0.5-10% by weight of a naphthenic acid salt, at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms, said substance being present in an amount from 1% to equal the weight of said naphthenic acid salt and at least one high boiling point monoether having the general formula:

wherein R' and R'' are selected from the group consisting of alkyl, aryl, aralkyl, alkaryl, and alicyclic radicals and at least one of the groups R' and R'' contains at least 6 carbon atoms, said high boiling point monoether being present in an amount of 10% to up to two times the weight of said naphthenic acid salt plus said substance.

10. As a new product, a hydrocarbon motor oil containing in solution between 0.5-10% by weight of barium naphthenate and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms, said substance being present in an amount from 1% to equal the weight of said barium naphthenate.

11. A liquid hydrocarbon solution consisting essentially of a liquid hydrocarbon; a naphthenic acid salt; and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms in an amount sufficient to form a solution of said naph-

thenic acid salt, said liquid hydrocarbon and said substance.

12. A liquid hydrocarbon solution consisting essentially of a liquid hydrocarbon; a naphthenic acid salt; and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 8 carbon atoms in an amount sufficient to form a solution of said naphthenic acid salt, said liquid hydrocarbon and said substance.

13. A liquid hydrocarbon solution consisting essentially of a liquid hydrocarbon; a naphthenic acid salt; and at least one substance having the general formula;

wherein R is an alkylene radical having a minimum of 2 and a maximum of 3 carbon atoms, n is a whole number between 2 and 7, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 8 carbon atoms in an amount sufficient to form a solution of said naphthenic acid salt, said liquid hydrocarbon and said substance.

14. A liquid hydrocarbon solution consisting essentially of a liquid hydrocarbon; a naphthenic acid salt; and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 12 carbon atoms in an amount sufficient to form a solution of said naphthenic acid salt, said liquid hydrocarbon and said substance.

15. A liquid hydrocarbon solution consisting essentially of a liquid hydrocarbon; a naphthenic acid salt; and at least one monoether of a radical selected from the group consisting of alkyl, aryl, aralkyl, alkaryl, and alicyclic radicals having at least 6 carbon atoms and a polyalkylene glycol having a minimum of 2 and a maximum of 3 carbon atoms in the alkylene group and having a maximum of 21 alkylene groups in an amount sufficient to form a solution of said liquid hydrocarbon, said naphthenic acid salt and said monoether.

16. A liquid hydrocarbon solution consisting essentially of a liquid hydrocarbon; a naphthenic acid salt; and at least one diether of a polyalkylene glycol having a minimum of 2 and a maximum of 3 carbon atoms in the alkylene group and having a maximum of 21 alkylene groups, said polyalkylene glycol being etherified at both ends of the polyalkylene glycol chain with a radical selected from the group consisting of alkyl, aryl, aralkyl, alkaryl, and alicyclic radicals at least one of which has at least 6 carbon atoms in an amount sufficient to form a solution of said liquid hydrocarbon, said naphthenic acid salt and said diether.

17. A liquid hydrocarbon solution consisting essentially of a liquid hydrocarbon; a naphthenic acid salt; and at least one monoester of an acyl radical selected from the group consisting of alkyl, aryl, aralkyl, alkaryl, and alicyclic radicals having at least 6 carbon atoms

and a polyalkylene glycol having a minimum of 2 and a maximum of 3 carbon atoms in the alkylene group and having a maximum of 21 alkylene groups in an amount sufficient to form a solution of said liquid hydrocarbon, said naphthenic acid salt and said monoester.

5 18. A liquid hydrocarbon solution consisting essentially of a liquid hydrocarbon; a naphthenic acid salt; and at least one diester of a polyalkylene glycol having a minimum of 2 and a maximum of 3 carbon atoms in the alkylene group and having a maximum of 21 alkylene groups, said polyalkylene glycol being esterified at both ends of the polyalkylene glycol chain with acyl radicals at least one of which has at least 6 carbon atoms in an amount sufficient to form a solution of said liquid hydrocarbon, said naphthenic acid salt and said diether.

10 19. A liquid hydrocarbon solution consisting essentially of a liquid hydrocarbon; a naphthenic acid salt; and at least one derivative of a polyalkylene glycol having a minimum of 2 and a maximum of 3 carbon atoms in the alkylene group and having a maximum of 21 alkylene groups, said polyalkylene glycol being etherified at one end of the polyalkylene glycol chain with a radical selected from the group consisting of alkyl, aryl, aralkyl, alkaryl, and alicyclic radicals and being esterified at the other end of said polyalkylene glycol chain with an acyl radical, at least one of said acyl, aryl, aralkyl, alkaryl, alicyclic radicals having at least 6 carbon atoms in an amount sufficient to form a solution of said liquid hydrocarbon, said naphthenic acid salt and said derivative.

carbon atoms said substance and said high boiling point monoether being present in an amount sufficient to form a solution of said liquid hydrocarbon, said naphthenic acid salt, said substance and said high boiling point monoether.

23. A liquid hydrocarbon solution consisting essentially of a liquid hydrocarbon; a naphthenic acid salt; at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms in an amount of 1% to equal the weight of said naphthenic acid salt; and at least one high boiling point monoether having the general formula:

wherein R' and R'' are selected from the group consisting of alkyl, aryl, aralkyl, alkaryl, and alicyclic radicals and at least one of the groups R' and R'' contains at least 6 carbon atoms in an amount of 10% to up to two times the amount of said naphthenic acid salt plus said substance.

24. A liquid hydrocarbon solution consisting essentially of a liquid hydrocarbon; a naphthenic acid salt; and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms in an amount of 1% to equal the weight of said naphthenic acid salt; and at least one high boiling point monoether liquid at room temperature and having the general formula:

wherein R' and R'' are selected from the group consisting of alkyl, aryl, aralkyl, alkaryl, and alicyclic radicals and at least one of the groups R' and R'' contains at least 6 carbon atoms and wherein both alkyl groups R' and R'' are derived from monohydric alcohols in an amount of 10% to up to two times the amount of said naphthenic acid salt plus said substance

25. A liquid hydrocarbon solution consisting essentially

ly of a liquid hydrocarbon; a naphthenic acid salt; and at least one substance having the general formula:

wherein R is an alkylene radical having a minimum of 2 and a maximum of 3 carbon atoms, n is a whole number between 1 and 20, and wherein one of the groups X and Y is selected from the class consisting of hydrogen, alkyl, aryl, aralkyl, alkaryl, alicyclic and acyl radicals and the other of said groups X and Y is selected from the class consisting of alkyl, aryl, aralkyl, alkaryl, alicyclic and acyl radicals having at least 6 carbon atoms in an amount of 1% to equal the weight of said naphthenic acid salt; and at least one high boiling point monoether liquid at room temperature and having the general formula:

wherein R' and R'' are selected from the group consisting of alkyl, aryl, aralkyl, alkaryl, and alicyclic radicals and at least one of the groups R' and R'' contains at least 6 carbon atoms and wherein at least one of the alkyl groups R' and R'' is derived from monohydric alcohols in an amount of 10% to up to two times the amount of said naphthenic acid salt plus said substance.

26. A liquid hydrocarbon solution consisting essentially of a liquid hydrocarbon; a naphthenic acid salt; and at least one monoether of a polyalkylene glycol having a minimum of 2 and a maximum of 3 carbon atoms in the alkylene group and having 5 alkylene groups, said polyalkylene glycol being etherified at one end of the polyalkylene glycol chain by an alkyl radical of 12 carbon atoms in an amount of 1% to equal the weight of said naphthenic acid salt, and with dodecyloctyl ether in an amount of 10% to up to two times the amount of said naphthenic acid salt plus said monoether.

27. A liquid hydrocarbon solution consisting essentially of a liquid hydrocarbon; a naphthenic acid salt; and at least one monoether of a polyalkylene glycol having a minimum of 2 and a maximum of 3 carbon atoms in the alkylene group and having 5 alkylene groups, said polyalkylene glycol being etherified at one end of the polyalkylene glycol chain by an alkyl radical of 12 carbon atoms in an amount of 1% to equal the weight of said naphthenic acid salt, and with dodecyl-2-ethylhexyl ether in an amount of 10% to up to two times the amount of said naphthenic acid salt plus said monoether.
